UNITED STATES PATENT OFFICE

172,119

TIME CONTROL VALVE

Peter H. Wilson, Barrington, R. I.

Application January 4, 1954, Serial No. 28,355

Term of patent 14 years

(Cl. D78—1)

To all whom it may concern:

Be it known that I, Peter H. Wilson, a citizen of the United States of America, residing in Barrington, county of Bristol, State of Rhode Island, have invented a new, original, and ornamental Design for a Time Control Valve, of which the following is a specification, reference being had to the accompanying drawing, forming a part thereof.

Fig. 1 is a side elevational view of a time control valve, showing my new design; and

Fig. 2 is a top plan view of a time control valve.

The dominant features of my design reside in the portions shown in full lines.

I claim:

The ornamental design for a time control valve, substantially as shown and described.
